UNITED STATES PATENT OFFICE.

ALBERT P. BALL, OF DETROIT, MICHIGAN, ASSIGNOR TO SQUARE D COMPANY, OF DETROIT, MICHIGAN, A CORPORATION OF MICHIGAN.

ELECTRIC SWITCH.

Application filed June 17, 1920, Serial No. 389,552. Renewed February 7, 1924.

To all whom it may concern:

Be it known that I, ALBERT P. BALL, a citizen of the United States, residing at Detroit, in the county of Wayne and State of Michigan, have invented new and useful Improvements in Electric Switches, of which the following is a full, clear, concise, and exact description, reference being had to the accompanying drawing, forming a part 10 of this specification.

My invention relates to electric switches and it has particular relation to apparatus of the character designated which embody means for ensuring a quick break between 15 the contacts when connection therebetween is broken as well as having in combination therewith means for ensuring a positive complete closure of the switch contacts when the connection is made.

20 The primary object of my invention is to provide means in combination with a switch of the character designated whereby the operating instrumentalities are so disposed that a decided resistance is interposed to the 25 accidental opening of the switch contacts by reason of jars or otherwise.

In the switch, hereinafter more specifically described, the positive closing connection is secured by the use of a slotted link 30 cooperating with the switch operating handle and having a portion at its lower end which engages with a spring latch, thus holding the switch in the "on" position until it is definitely opened by the operation of 35 the operating handle. In this connection I provide springs so associated with the movable contacts of the switch that the latter are continuously biased towards the open position thereof, and the switch will not 40 therefore remain closed until the movable contacts are thrown to such a position that the link hook and the spring latch are engaged whereby the tendency of the movable contacts to snap to the open position there- 45 of is overcome.

The hook and the spring latch are so disposed that the latter interposes a decided resistance to the closing of the movable contacts just before the latter make engagement 50 with appropriate stationary contacts. It is necessary, therefore, to exert additional pressure on the operating handle in order to overcome this resistance. Inasmuch as the movable switch blades need only move a 55 short distance thereafter to be completely

closed, this additional pressure, necessary to overcome the resistance, results in the remainder of the blade travel being involuntarily made with considerable rapidity. The operation just described, therefore, results 60 in a very advantageous quick action of the switch contacts upon making the connection.

After the link has once engaged the spring latch a decided resistance is interposed to the opening movement of the operating handle whereby the accidental disconnection of the contacts by jarring or accidental contact is prevented. As I will hereinafter more 65 fully point out this feature is obtained by the specific positioning of the operating handle in a specifically shaped slot formed in the aforementioned link.

For a better understanding of my invention reference may be had to the accompanying drawing, in which :

Fig. 1 is a plan view of a switch embodying my invention positioned in an enclosed casing, the cover thereof being removed;

Figs. 2, 3 and 4 are elevational, sectional views taken on the line 2—2 of Fig. 1, and 70 illustrate the positions of the various switch operating elements at three different points in the operation thereof.

A casing 1 is provided with a hinged cover 2, the latter being removed in Fig. 1. Secured to the bottom of the casing 1 is an insulating switch base 3 having fuse receiving clips 4 and 5 mounted thereupon, a fuse 6 extending between the said clips, and binding posts 7 being associated with the clips 85 adjacent one end wall of the casing 1. Stationary switch contacts 8 and 9 are likewise mounted upon said base, the contacts 8 being electrically connected to the fuse clips 4 and providing a pivotal support for movable 90 contact blades 10. Suitable binding posts 11 are associated with the contacts 9. A cross-bar 12 is rigidly connected to the movable blades 10 by clamps 13, the blades, clamps and cross arm moving together on 95 the opening and closing movements of the switch.

A switch operator comprises a handle 14 and a bail shaped portion 15 formed integrally therewith, said operator being adapted for rotation by reason of its pivotal support in the side walls of the casing 1. Washers 16 serve to pivotally position a link 17 on the cross-arm 12. The latter has formed therein an arcuate slot 18 and is shaped at 100

its lower end to provide a hook portion 19. Mounted on the base 3 is a spring 20 which is formed with a yoke portion 21 about which is loosely journaled a roller 22. The cross-
5 arm of the bail shaped portion 15 is adapted to slide over one end to the other of the slot 18 as the link 17 moves pivotally about the cross-arm 12.

10 Springs 23 are secured at one end to the switch posts 8 and have a yoke portion 24 which extends under the movable contacts 10 in such manner that the latter are constantly biased to an open position, shown in Fig. 4.

15 Having described one embodiment of my invention the operation thereof is as follows:

Upon a switch-closing movement of the handle 14 the switch operator 15 slides in the 20 slot 18 to the left hand end thereof, as shown in Fig. 2, and thereafter presses the movable contacts 10 downwardly until the hook 19 of the link 17 comes into contact with the roller 22 on the spring 20. This obstruction is met just prior to the initial engagement of the switch contacts. Upon the application of additional pressure on the operating handle the hook pushes the spring to the right and, as soon as the roller is 25 passed, the movable contacts make a definite and positive engagement with the stationary contacts comparatively rapidly. Thereafter, the normal bias of the spring 20 effects a latching engagement between said spring 30 and the hook 19 whereby the opening action of the springs 23 is overcome. The position of the various switch elements in the closed and latched position of the movable contacts is shown in Fig. 2.

40 The contour of the hook is such that the resistance to the closing of the switch is interposed just before the blades enter the switch jaws. It is apparent therefore that unless the required additional pressure is ap-

45 plied to the switch operating handle the blades will spring back under the action of the spring 23 and the connection will not be made. This operation is of distinct advantage in that it prevents incomplete closing, and consequent high contact resistance 50 between the contacts. Part 15 is forced into slot 18 by springing the link at 17.

55 On the other hand, when it is desired to open the switch, the operating handle is moved to the right until the part 15 engages the right hand end of the slot 18 whereupon the link 17 is rotated about its pivotal support on the arm 12 to disengage the hook from its latching relation with the spring 60 20. The position of the switch elements just after the link has been rotated to effect said disengagement is shown in Fig. 3.

65 Immediately upon said disengagement the springs 23 function to snap the switch blades open, the length of the slot 18 being such that

the link rides past the member 15 without effecting a movement thereof. The position of the switch blade, the link and the handle at this time are shown in Fig. 4.

I find it distinctly advantageous to use a 70 spring latch having a roller mounted upon the yoke portion thereof, as heretofore described, because of the beneficial reduction in wear and friction which may be obtained by such combination. This particular latch 75 also provides tension in two directions which is beneficial in providing the desirable features herein described with respect to the shape of the slot in the link.

In order to prevent a switch opening movement of the operating handle due to its own weight or because of vibration whereby the member 15 might reach the end of the slot and through jarring or accidental contact unlatch the link, the slot is 80 so shaped that the operating lever in traversing it from one end to the other acts so as to latch the hook on the link more securely with the spring 20. The increased resistance thus provided prevents the operating handle from jarring downwardly when my switch is mounted in an upright position, inasmuch as the handle in its initial movement through the slot instead of tending to unlatch the switch, emphasizes the engagement 85 between the hook and the spring. It is necessary, therefore, to make a definite positive movement of the handle 14 whereby the member 15 is moved from one end of the slot 18 to the other before the latching engagement is unlocked and the movable blades permitted to snap open.

90 While I have described but one embodiment of my invention it is apparent that many modifications therein may occur to those skilled in the art and I desire, therefore, that it be limited only by the showing of the prior art and by the scope of the appended claims.

Having thus described my invention 100 what I claim as new and desire to secure by Letters Patent is:

1. In a switch, stationary and movable contacts, an operator, means connecting said movable contacts and said operator, means for interposing resistance to the closing of said movable contacts, said connecting means so associating said movable contacts and said operator that a definite positive movement must be applied to said operator to open said contacts and being further so associated that an initial switch opening movement of said operator emphasizes said resistance, whereby accidental partial movement of the operator does not open said switch.

110 2. In a switch, stationary and movable contacts, an operator, means connecting said movable contacts and said operator, means for interposing resistance to the 115

closing of said movable contacts and thereafter comprising a retaining member for said contacts, said connecting means so associating said movable contacts and said operator that, after said contacts have been definitely retained in closed position, a definite positive movement must be applied to said operator to open said contacts and being further so associated that

10 an initial switch opening movement of said operator emphasizes said resistance whereby partial accidental movement of the operator does not open said switch.

3. In a switch, stationary and movable contacts, an operator, means comprising a link, connecting said movable contacts and said operator, means for interposing resistance to the closing of said movable contacts and for thereafter latching the same

20 through said link, said connecting means so associating said movable contacts and said operator that a definite positive movement must be applied to said operator to open said contacts whereby accidental movement of the latter does not open said switch.

4. In a switch, stationary and movable contacts, an operator, means connecting said movable contacts and said operator, comprising a link having a slot therein in which part of said operator slides, and means for interposing resistance to the closing movement of said movable contacts and for thereafter engaging one end of said link to lock said contacts in closed position,

30 said slot being so shaped that said operator in making a switch-opening movement initially emphasizes said locking.

5. In a switch, stationary and movable contacts, an operator, means connecting said movable contacts and said operator, comprising a link having a slot therein in which part of said operator slides, and means for interposing resistance to the closing movement of said movable contacts

45 and for thereafter engaging one end of said link to lock said contacts in closed position, said slot being arcuate in such direction that said operator in making a switch-opening movement initially emphasizes said locking,

50 whereby accidental movement of the latter does not open said switch.

6. In a switch, stationary and movable contacts, an operator, means connecting said movable contacts and said operator, means for locking said movable contacts in closed position, and means whereby an initial switch-opening movement of the operator emphasizes the locking and thus interposes

resistance to an accidental movement of said operator in a switch-opening direction.

7. In a switch, stationary and movable contacts, an operator, means for locking said movable contacts in closed position, and means for connecting said movable contacts and said operator comprising a link having a slot therein in which said operator slides, said slot being arcuate in such direction that resistance is interposed to an accidental opening of said switch whereby a positive engagement of said operator with the end of said slot is necessary to unlock said contacts and open said switch.

8. In a switch, stationary contacts, movable contacts biased to an open position, an operator, a pivoted link having a slot therein for connecting said operator to said contacts, and a latching device for said movable contacts comprising a spring having an oscillatory yoke portion, one end of said link being adapted to engage said yoke portion and to be locked by the normal bias thereof.

9. In a switch, stationary contacts, movable contacts biased to an open position, an operator, a pivoted link having a slot therein for connecting said operator to said contacts, and a latching device for said movable contacts comprising a spring having an oscillatory yoke portion provided with a roller, one end of said link being adapted to engage said roller and to be locked by the normal bias of said spring.

10. In a switch, stationary contacts, movable contacts biased to an open position, an operator, a pivoted link having a slot therein for connecting said operator to said contacts, and a latching device for said movable contacts comprising a spring having an oscillatory yoke portion, one end of said link being adapted to engage said yoke portion and to be locked by the normal bias thereof, and said slot being arcuate in such direction that said operator in sliding therein during its initial switch-opening movement emphasizes said locking and only functions to unlock said link and said latch when it engages the end of said slot, whereby an accidental or incomplete switch-opening movement of said operator meets an increased resistance.

In witness whereof, I have hereunto subscribed my name.

ALBERT P. BALL.
